GUN

August Dabrowsky, Washington, D. C., assignor to
the Government of the United States of Amer-
ica, as represented by the Secretary of War

Application February 4, 1938, Serial No. 188,683

6 Claims. (Cl. 89—37)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a gun.

Because high speed aircraft is within the range of an antiaircraft gun for only a short period of time it is necessary to develop a high rate of fire to increase the probability of hitting the target.

10 With a modern 3 inch antiaircraft gun it is possible to load and fire at the rate of forty rounds per minute but the gun barrel becomes overheated and due to expansion of the metal its movement in the cradle during recoil and 15 counterrecoil is interfered with and frequently prevented.

15 The purpose of this invention is to provide a gun barrel mounting which will allow for radial and longitudinal expansion of the barrel and 20 which will enable the barrel to be cooled sufficiently to insure its reciprocation in the cradle while maintaining a maximum rate of fire.

25 A further object is to provide a mounting which will facilitate the rapid and convenient removal and replacement of the gun barrel.

To these and other ends, the invention consists in the construction, arrangement and combination of elements described hereinafter and pointed out in the claims forming a part of this 30 specification.

A practical embodiment of the invention is illustrated in the accompanying drawings, wherein:

Fig. 1 is a plan view, partly in section, of a gun constructed in accordance with the invention.

35 Fig. 2 is a view in side elevation with the cradle in section.

Figs. 3 and 4 are views, respectively in side elevation and in plan of one of the rails.

Fig. 5 is a sectional view on the line 5—5 of 40 Fig. 1.

Fig. 6 is a sectional view on the line 6—6 of Fig. 5.

Figs. 7 and 8 are sectional views on the corresponding lines of Fig. 3.

45 Referring to the drawings by characters of reference there is shown a cradle 5 which is provided with trunnions 6 whereby it is mounted in a carriage (not shown) for movement in elevation. The lower portion of the cradle which carries the recoil and counterrecoil mechanism has been omitted. The cradle includes a pair of spaced, forwardly extending arms 7—7 whose lower sides are connected by a thin ribbed plate 8 to afford rigidity. The forward portion of the 50 plate is formed with a plurality of openings 9

which in addition to reducing the weight serves to permit free circulation of air. The front extremities of the arms are further strengthened by an overhead arcuate plate 10. The inner sides of the arms are each provided with a groove 11.

5 The gun which is to be mounted on the cradle comprises a breech ring 12 and a barrel 13 whose rear end has an interrupted thread connection 14 with the breech ring. A pair of similar rails 15—15, each including wearing strips 16, are secured to the opposite sides of the breech ring by means of screws 17 and each rail has a lug 18 engageable in a recess in the breech ring. The rails are slidably mounted in the grooves 11 of the cradle arm 7 and extend some distance in front of the arms to allow for movement of the gun in recoil.

10 A supporting ring 19 disposed between the rails near their front ends and forwardly of the cradle arms 7 is formed with a pair of aligned lugs 20—20 each of which is received in a recess 21 in the corresponding rail and secured by screws 22. The internal surface 23 of the ring 19 is rearwardly tapered (Fig. 6) and supports an expansion ring 24 having a correspondingly tapered external surface 25. The rear portion of the expansion ring is formed with internal threads 26 which engage threads 27 on the gun barrel and it is held in place by a set screw 28. A plurality of arcuate grooves 29—29 are cut in the front 15 and rear faces of the expansion ring.

20 By reference to Fig. 1 it will be noted that the internal diameter of the supporting ring 19 is greater than the external diameter of all portions of the barrel in rear thereof so that it is possible to move the barrel through the supporting ring. This construction facilitates the removal and replacement of barrels without disturbing the breech ring 12 and the rails 15 and the connections of the breech ring to the recoil and counterrecoil 25 mechanisms (not shown).

25 Since the rails 15 and the cradle arms 7 are spaced an appreciable distance from the gun barrel 13 they do not become overheated during firing and prevent movement of the gun. The front support of the gun barrel is at about its center, well forwardly of the cradle arms, and the expansion ring is specially designed to minimize heat conduction.

30 Radial and longitudinal expansion of the gun barrel will be taken care of by the expansion ring 24 and its mounting in the supporting ring.

I claim:

35 1. In a gun, a cradle including a pair of arms each having a groove on its inner side, a breech

55

ring within the cradle, a pair of rails on the breech ring slidably mounted in the grooves of the cradle arms and extending forwardly of said arms, a gun barrel detachably connected to the breech ring and spaced from the rails, a supporting ring carried by the rails and disposed forwardly of the cradle arms, said ring having a rearwardly tapered internal surface, and an expansion ring carried by the gun barrel and having a rearwardly tapered external surface fitting in the supporting ring, the front and rear faces of the expansion ring provided with arcuate grooves. 5

2. In a gun, a cradle including a pair of arms each having a groove on its inner side, a breech ring within the cradle, a pair of rails on the breech ring slidably mounted in the grooves of the cradle arms and extending forwardly of said arms, a gun barrel connected to the breech ring and spaced from the rails, a supporting ring carried by the rails and disposed forwardly of the cradle arms, said ring having a rearwardly tapered internal surface, and an expansion ring carried by the gun barrel and having a rearwardly tapered external surface fitting in the supporting ring. 10

3. In a gun, a cradle, a breech ring having a pair of rails slidably mounted in the cradle, a gun barrel connected to the breech ring and spaced from the rails, a supporting ring carried

by the rails forwardly of the cradle and having a rearwardly tapered internal surface, and an expansion ring carried by the gun barrel and having a rearwardly tapered external surface fitting in the supporting ring. 5

4. In a gun, a cradle, a breech ring having a pair of rails slidably mounted in the cradle, a gun barrel connected to the breech ring and spaced from the rails, a supporting ring carried by the rails forwardly of the cradle and an expansion ring carried by the gun barrel and fitting in the supporting ring. 10

5. In a gun, a cradle, a breech ring having a pair of rails slidably mounted in the cradle, a gun barrel connected to the breech ring and spaced from the rails, a supporting ring carried by the rails and an expansion ring carried by the gun barrel and fitting in the supporting ring. 15

6. In a gun, a cradle, a breech ring having a pair of rails slidably mounted in the cradle, a gun barrel detachably connected to the breech ring, a supporting ring carried by the rails and having an internal diameter greater than the external diameter of the gun barrel whereby the barrel is movable through said ring, and a ring carried by the barrel and disposed in the supporting ring. 20

AUGUST DABRASKY.
